UNITED STATES PATENT OFFICE.

CHARLES HIBBARD, OF HUDSON FALLS, AND WARREN HIBBARD, OF FORT EDWARD, NEW YORK.

RIM TOOL.

Application filed January 12, 1922. Serial No. 528,747.

To all whom it may concern:

Be it known that we, CHARLES HIBBARD and WARREN HIBBARD, citizens of the United States, and residents, respectively, of Hudson Falls, in the county of Washington, and State of New York, and Fort Edward, in the county of Washington, and State of New York, have invented a new and Improved Rim Tool, of which the following is a full, clear, and exact description.

This invention has relation to tools and particularly refers to a rim tool for automobile tires which is designed as a means for facilitating the association and disassociation of tires and rims in a simple, expeditious and efficient manner.

Heretofore many tools of this character have been devised for this purpose, but have been found wanting in many respects due to the fact that they have failed to overcome certain contingencies. It is therefore the principal object of the present invention to produce a rim tool which will completely and effectually handle the rim to facilitate the disassociation of the tire therewith by shifting and disengaging the locking means at the rim joint and contracting and holding the rim in a contracted condition while the tire is removed; facilitating the association of the tire and rim by expanding the rim, and shifting and interengaging the locking means at the joint.

As a further object the invention affords means for compensating for the deflection of the ends of the rim at the joint where the same have been bent or otherwise distorted to normally lie out of true alignment.

As a still further object the invention contemplates a comparatively simple and inexpensive tool which may be arranged to occupy a minimum amount of space when not in use whereby the same may be readily carried in the tool box of a vehicle for use on the road, and which will form a useful part of the equipment of garages, repair shops and service stations.

With the above recited and other objects in view, the invention resides in the novel construction set forth in the following specification, particularly pointed out in the appended claims and illustrated in the accompanying drawings, it being understood that the right is reserved to embodiments other

than those actually illustrated herein to the full extent indicated by the general meaning of the terms in which the claims are expressed.

In the drawings—

Figure 1 is a side elevation illustrating the device in applied position on a rim.

Fig. 2 is an enlarged fragmentary bottom plan view thereof.

Fig. 3 is a fragmentary longitudinal sectional view illustrating the initial shifting operation of the rim locking means to unlocked position.

Fig. 4 is a similar view illustrating the contracting operation of the rim.

Fig. 5 is a transverse sectional view taken approximately on the line 5—5 of Fig. 1.

Fig. 6 is a detail transverse sectional view taken on the line 6—6 of Fig. 1.

Figs. 7 and 8 are fragmentary longitudinal sectional views illustrating a distorted rim and the manner in which the same is compensated for.

Fig. 9 is an end view.

Fig. 10 is a detail transverse sectional view taken approximately on the line 10—10 of Fig. 8.

Fig. 11 is a fragmentary detail view of the pawl and ratchet.

Figs. 12 and 13 are fragmentary longitudinal sectional views illustrating a distorted rim and a modified form of means for compensating for the same.

Fig. 14 is an end view of the same.

Fig. 15 is a bottom plan view thereof.

Referring to the drawings by characters of reference A designates one of the common forms of demountable tire rims which is split as at B and provided with one of the common forms of locking means C for retaining the ends in locked condition to hold the rim in ring form within the tire. Specifically the locking means embodies a slot in one of the rim terminals and a lug E provided with an offset extremity F which engages within the slot D.

The tool which constitutes the invention includes a pair of rim clamping members designated generally by the characters 10 and 11 which are connected together for relative movement. The member 10 comprises a base plate 12 provided on its under side with depending forwardly projecting laterally spaced arms 13 preferably forming integral

elements thereof. The member 10 further includes clamping jaws 14 hinged to the opposite sides of the base plate 12 by a hinge pin 15 which passes through aligned pairs of knuckles 16 and 17 formed respectively on the base plate and clamping jaws. The upper extremity of the jaws 14 are provided with spaced pairs of rim engaging hooks 18 by means of which the member is associated with the rim. A clamping bolt 19 is passed through aligned apertures 20 in the jaws 14 for locking and retaining the rim engagaing hooks in clamping relation to the rim. The inner or rear portions of the arms 13 are provided with aligned bearing openings 21 in which a transverse shaft 22 is mounted and upon which a sprocket wheel 23 is arranged between the arms 13 and keyed as at 24 to the shaft. A ratchet 25 is keyed to the shaft 22 at the outer side of one of the arms 13 and the shaft 22 projects therebeyond and is provided at its outer extreme end with a multi-faced extremity 26 with which a wrench or crank may be associated for rotating the shaft. The outer or forward free extremities of the arms 13 are apertured to receive a transverse stub shaft 28 upon which an idler roller 29 is mounted and arranged between the arm terminals and a sprocket chain 30 is trained over the sprocket wheel 23 and idler roller 29. A pawl 31 is pivotally mounted as at 32 on one of the arms 13 and is normally engaged with the ratchet 25 by a leaf spring 33 to limit the rotation of the shaft 22 for turning movement in one direction when engaged therewith. The pawl 31 is provided with a pair of spring engaging faces 34 and 35 in order to provide means for respectively throwing the pawl into and out of engagement with the teeth of the ratchet when desired.

The member 11 comprises a base plate 40 which has hinged to the opposite side edges thereof a pair of clamping jaws 41 by means of a hinge pin 42 which passes through aligned pairs of knuckles 43 and 44 formed respectively on the base plate and the clamping jaws. The upper extremity of the jaws 41 are provided with spaced pairs of rim engaging hooks 45 by means of which the member is associated with the rim. A clamping bolt 46 is passed through aligned apertures in the jaws 41 for locking and retaining the rim engaging hooks in clamped relation to the rim. The outer or rear end of the base plate 40 is provided with depending spaced hinge lugs 48 which receive therebetween a spaced pair of hinge lugs 49 of a complementary base plate 50 and a hinge pin 51 is passed through the lugs 48 and 49 to hingedly connect the complementary base plate 50 with the base plate 40. The complementary base plate 50 is provided with depending and forwardly projecting laterally spaced arms 51

which are connected at their forward free extremities to the sprocket chain 30 by one of the link pins 52. The threaded shank 53 of a wing screw 54 extends through a threaded aperture 55 in the complementary base plate 50 and the inner end of the shank is swiveled to the base plate 40 as at 56 whereby rotation of the wing screw in opposite directions will respectively effect the advancement or relative separation of the base plate 40 and complementary base plate 50.

In operation of the tool, when it is desired to remove the tire from the rim, the members 10 and 11 are attached to the rim A at opposite sides of the joint B by engaging the clamping jaws 14 and 41 therewith. In attaching the members to the rim, the link pin 52 which connects the arms 51 with the sprocket is disposed at the upper portion of the idler roller 29. The tool is then ready for operation to effect the removal of the tire by associating a wrench or crank with the multifaced extremity 26 of the shaft 22 and rotating the same. The initial operation of the device by the movement of the link pin 52 around the idler roller 29 effects a relative separation of the ends of the rim to shift the offset extremity F into a position to be removed from the slot D. The next movement of the link pin 52 as indicated by the arrow in Fig. 3 effects a downward movement of one rim extremity with respect to the other to disengage the offset extremity F from the slot. At this point the pin 52 together with the forward extremities of the arms 51 of the member 11 have been moved toward the underside of the idler roller 29 and continued movement of the sprocket chain 30 will advance the member 11 toward the member 10 and the terminal of the rim A clamped thereby under the other terminal to effect a radial contraction of the entire rim. The engagement of the pawl 31 with the ratchet on the shaft 22 will retain the rim in its contracted condition to permit the operator to readily remove the tire from the rim.

When the rim is thus contracted and it is desired to apply a tire thereto, the tire is placed over the rim and the pawl 31 is swung upon its pivot 32 to dispose the same out of engagement with the ratchet. The shaft 22 is then rotated in the reverse direction to effect a relative separation of the members 10 and 11 and the resulting expansion of the rim A until the link pin 52 reaches the forward or outer extent of its movement. Continued movement of the sprocket chain will effect the raising of the depressed rim terminal into alignment with the other rim terminal and at the same time the entrance of the offset F into the slot D. The final movement of the sprocket chain will cause the rim terminals to be advanced toward each other and the shifting of the offset terminal to

locking engagement within the slot, thereby completing the application of the rim to the tire.

In event of the rim being distorted as illustrated in Fig. 7, the same may be compensated for by manipulating the wing screw 54 to separate the base plate 40 from the complementary base plate 50 to lift and dispose the rim terminals in alignment prior to the final step of the operation of advancing the rim terminals into engagement and the offset extremity F of the locking lug into locking engagement with the slot D as illustrated in Fig. 8. It will thus be seen that a rim tool has been provided for facilitating the association and disassociation of tires and rims in a simple, expeditious and efficient manner, together with means for compensating for distorted rims.

In the modified form illustrated in Figs. 12 to 15 exclusive an eccentric 60 mounted on a transverse pin 61 and provided with a manipulating handle 62 is carried by the forwardly projecting laterally spaced arms 51 of the member 11, while the pin 64 is mounted transversely in the laterally spaced ears 65 of the base plate 40. The eccentric and link connection is employed in the modified form in lieu of the wing screw 54 for effecting relative separation between the base plate 40 and the arms 51 to compensate for distorted rims and dispose the rim terminals in alignment prior to the final step of the operation to advance the rim terminals into engagement and the offset extremity F of the locking lug into locking engagement with the slot D as illustrated in Fig. 13.

We claim:

1. A rim tool comprising a pair of members adapted for detachable connection respectively to the opposite ends of a split rim, an endless flexible element mounted for movement on one of the members, and a connection between said element and the opposite member for effecting respectively the contraction and expansion of the split rim upon movement of said flexible element in opposite directions.
2. A rim tool comprising a pair of members adapted for detachable connection respectively to the opposite ends of a split rim, an endless flexible element mounted for movement on one of the members, a connection between said element and the opposite member for effecting respectively the contraction and expansion of the split rim upon movement of said flexible element in opposite directions, and means for locking the flexible element against movement for holding the rim in contracted condition.
3. A rim tool comprising a pair of members adapted for detachable connection respectively to the opposite ends of a split rim, a pair of spaced rotary guides carried

by one of said members, an endless flexible element mounted for movement on said guides, and a connection between said element and the opposite member for effecting respectively the contraction and expansion of the split rim upon movement of said flexible element in opposite directions.

4. A rim tool comprising a pair of members adapted for detachable connection respectively to the opposite ends of a split rim, a pair of spaced rotary guides carried by one of said members, an endless flexible element mounted for movement on said guides, a connection between said element and the opposite member for effecting respectively the contraction and expansion of the split rim upon movement of said flexible element in opposite directions, and a positive driving connection between one of the rotary driving guides and the flexible element for effecting movement of the flexible element upon manipulation of said guide.

5. A rim tool comprising a pair of members adapted for detachable connection respectively to the opposite ends of a split rim, a pair of spaced rotary guides carried by one of said members, an endless flexible element mounted for movement on said guides, a connection between said element and the opposite member for effecting respectively the contraction and expansion of the split rim upon movement of said flexible element in opposite directions, a positive driving connection between one of the rotary driving guides and the flexible element for effecting movement of the flexible element upon manipulation of said guide, and means for locking said rotary guide to hold the flexible element against movement and the rim in its contracted condition.

6. A rim tool comprising a pair of members adapted for detachable connection respectively to the opposite ends of a split rim, a pair of spaced rotary guides carried by one of said members, an endless flexible element mounted for movement on said guides, a connection between said element and the opposite member for effecting respectively the contraction and expansion of the split rim upon movement of said flexible element in opposite directions, a positive driving connection between one of the rotary driving guides and the flexible element for effecting movement of the flexible element upon manipulation of said guide, means for locking said rotary guide to hold the flexible element against movement and the rim in its contracted condition, and means on the opposite member for compensating for the distortion of the rim ends.

7. A tool for effecting the association and disassociation of a tire shoe or casing with a split rim, including a pair of members each provided with means for clamping the same respectively to the opposite extremities

of the rim, and a connection therebetween
operable to respectively release the rim ex-
tremity locking means and for contracting
the rim for disassociation of the tire and rim
and for expanding the rim and engaging the
rim extremity locking means for associat-
ing the tire and rim with each other,
said connection comprising an endless flexi-

ble element mounted on one of the members
for movement in opposite directions, spaced 10
guide elements over which said flexible ele-
ment is trained in its movement, and a con-
nection between the opposite member and
said flexible element.

CHARLES HIBBARD.
WARREN HIBBARD.
